J. L. NILSON AND J. PRINCE,
VEHICLE WINDSHIELD,
APPLICATION FILED FEB. 26, 1919.

1,349,430.

Patented Aug. 10, 1920.

UNITED STATES PATENT OFFICE.

JOHN L. NILSON AND JOHN PRINCE, OF CHICAGO, ILLINOIS.

VEHICLE-WINDSHIELD.

1,349,430.

Specification of Letters Patent. Patented Aug. 10, 1920.

Application filed February 26, 1919. Serial No. 279,342.

To all whom it may concern:

Be it known that we, JOHN L. NILSON and JOHN PRINCE, citizens of the United States, residing at Chicago, in the county of Cook and State of Illinois, have invented certain new and useful Improvements in Vehicle-Windshields, of which the following is a specification.

Our invention relates to wind shields and has particular reference to devices designed to protect transparent wind shields of automobiles and the like against being blurred and the driver's vision ahead being interfered with during rain or snow fall. The objects of the invention are to provide a protective attachment for this purpose that shall be of light weight, low cost, easily attached or dismounted, and which may be attached to the wind-shield itself thus obviating the need of special supports for this purpose mounted on the frame of the vehicle itself. Another object of the invention is to provide a wind shield canopy, curtain or protector of universal application, or which may be applied to the wind shields that are in general use, and either carried thereupon when not in use as an unobtrusive portion or edge of the wind shield itself or packed away in a small space. With these general objects in view our invention consists in the novel construction, combination and arrangement of parts, all as hereinafter described in detail, illustrated in the accompanying drawing and incorporated in the appended claims.

In the drawing—

Figure 1 is a plan view of a wind-shield protector, canopy, awning, or curtain embodying our invention and shown in operative position.

Fig. 2 is an enlarged end view of same with a broken away portion of the usual form of wind shield.

Fig. 3 is an enlarged section taken substantially on the line 3—3 of Fig. 1 and partly broken away.

Fig. 4 is a section taken on line 4—4 of Fig. 3.

Fig. 5 is an enlarged section taken substantially on the line 5—5 of Fig. 4.

Fig. 6 is an edge view of the trough or drain-channel portion of the curtain broken away.

Fig. 7 is a section taken substantially on the line 7—7 of Fig. 3.

In the several views 2 represents a usual top rail or glass wind shield frame portion

for the transparent plate 3, and 4 and 5 represent vertical or end portions of such a frame. In the views our improvement is shown attached to the upper frame rail 2, but our form of attachment is equally as well adapted for engagement with the plate 3 itself if mounted without a frame portion 2.

Generally speaking, our invention may be said to be an awning adjustable at any desired angle with reference to the wind shield, said awning being mounted upon a roller, axis, core or frame-side and adapted to be rolled upon same into a compact roll which includes the four sides of a metallic frame for said awning, three of said sides being within the roll and the fourth lying upon it. Our construction is designed to be very light in weight; to provide a flexible awning-body of cloth or other suitable material, including celluloid and the like, and a comparatively rigid frame for said body when in operative position. In the present embodiment of our invention we make one rail or frame side in the form of a cylindrical casing adapted to contain two of the other sides of the frame, but the details of construction which provide an awning and

an awning frame of comparatively rigid members, all of which may be formed into a small roll, may be varied in numerous ways without departing from the spirit of our invention. The long parallel sides of the frame referred to consists of transversely bent sheet metal strips 6 and 7 to

which opposite or parallel edges of a flexible awning or curtain 8 are secured. The frame portion 6 is in the form of a hollow roller or cylinder upon which the curtain or awning 8 is wound in the form of a roll when not in use, as in Figs. 4 and 5. The roller 6 is in cross section only approximately two-thirds of a circle, which

provides an opening thereinto extended throughout its length and is designated by the numeral 9. Through this opening the end rails of the frame are folded upon each other within said roller. For this purpose the ends of the roller or casing 6 are provided with pivot pins or spindles 10 and 11 which diametrically span the interior space of the member 6 and have their ends riveted or otherwise secured to opposite sides of said member.

The construction in connection with these pivots is the same at each end of the member 6, being in Fig. 5 shown partly in section at the left hand end while

exterior views of the same parts are shown at the right hand end of said figure.

Upon the pivot pins 10 and 11 are mounted screw-threaded studs or trunnions 12 and 5 12' which carry thumb or butterfly nuts 13 and 13'. These pivot pins pass through circular disks 14 and 14' each with a knurled edge 15. The trunnions 12 and 12' are revolvably mounted in apertured ears or lugs 16 10 and 17 which are bent out ends of a bar or flat strip of metal 18 that serves as a support for the canopy roll and is itself supported on the wind shield by means of, preferably, integral spring lugs, hooks, or clamp 15 members 19 that are frictionally engaged with the edge of the wind-shield or its frame as shown in Figs. 1, 2 and 3. The trunnion or stud 12 or 12' has a key-slot 20 therein that is engaged by an inwardly projecting 20 key or lug 21 that extends from the edge of a bore 22 in the disk 14 or 14' and is engaged by the stud 12, 12'. The disk 14 or 14' and the roller and casing 6 are held and caused to revolve together by reason of said disk 25 being keyed to the trunnion 12 or 12' through which the pivot pin 10 passes and said pin having its ends secured to the member 6.

On the pivot pins 10 and 11 are mounted 30 arms or frame-rails 23 and 24 each of which has thereon or as a part thereof a forked hinge-knuckle portion 25 that straddles the trunnion. Said knuckle portions are pivoted upon the pivot pins 10 and 11. In Fig. 1 35 the arms 23 and 24 are shown extended from their casing and arranged as a part of a four-sided frame for the awning 8. In Fig. 4 said arms are shown folded upon each other within the roller 6. Each of these 40 arms is a strip of sheet metal bent transversely substantially U-shape, as shown in Figs. 5 and 7. At their free ends the U-shaped channels frictionally engage the ends of the frame side or rail 7 (Fig. 1) the latter being inserted in the channels which is 45 separately indicated by the numeral 27 in Fig. 7. When the nuts 13 and 13' are tightened against the knurled disks 14 and 14' the pivot ends of the arms are clamped 50 against the ears 16 and 17 and held rigidly extended in operative position and in engagement with the ends of the frame portion 7. The latter is also a sheet metal strip bent transversely upon itself and between 55 the overlaps the outer edge of the curtain is held, as shown in Figs. 2, 3, 5, 6 and 7. The two-ply curtain edge or frame-rail 7 is also bent, as shown, at an obtuse or other suitable angle transversely to form a trough, channel, spout, or gutter 28 which is adapted to 60 drain water from the canopy to one of its ends and prevent drops of water being blown against the wind shield plate 3. The channel form of the frame portion 7 also functions as a stop holding the part 7 at the 65

ends of the arms 23 and 24 by one side of the trough 28 overlying one side of the U-shape channel of each arm. The angle iron form of the member 7 also serves as a stop to hold the outer edge of the canopy in place when it is rolled up, as shown in Fig. 5 where the trough 28 is held against passing through the space between the frame portion 18 and the rolled up curtain, its roll form being separately identified by the numeral 8'. The 70 inner edge of the curtain or canopy 8 is held on the roller 6 by forming a bend 29 in one of its edges and clamping the overlapping parts upon the edge of the canopy in the manner shown in Figs. 3, 4 and 5. While 75 the hinge or knuckle portions 25 are shown as separate members secured to the arms 23 and 24 by means of rivets 30 and 31 our construction is well adapted for making the knuckle portions integral with the arms. 80

We claim as our invention—

1. The combination with a wind shield, of a hollow roller and frame sides adapted to be folded within said roller, an awning or curtain adapted to be rolled upon said roller, 90 and means for attaching said awning or curtain to said wind shield.

2. The combination with a wind shield, of a hollow roller mounted on said wind shield, a flexible sheet adjustable to screen said wind shield; and a frame for said sheet when in operative position the bars or sides of which frame fold upon each other within said roller and together with said roller form a core upon which said sheet may be 100 rolled up.

3. The combination with a wind shield, of a rotatably mounted frame member, a flexible sheet having one of its edges attached to said member, a comparatively rigid frame member lining attached to the opposite edge of said sheet, a pair of end frame members pivoted to said rotatably mounted frame member and adapted to fold therewithin, and means for temporarily or separably coupling the free ends of said end frame members to the ends of said comparatively rigid frame member. 105

4. The combination with a wind shield, of a revolvably mounted casing, a pair of arms pivoted each at one end at the ends of said casing and folding upon each other therewith, a flexible sheet attached at one end or side to said casing and having a comparatively rigid rib on the opposite end or side, 110 means for coupling and arranging said casing, arms and rib to form a frame for said sheet, means for variably adjusting the angle of inclination of said frame relative to said wind shield, and means which detachably hold said frame on said wind shield. 115

In testimony whereof we have hereunto signed our names:

JOHN L. NILSON
JOHN PRINCE.
